UNITED STATES PATENT OFFICE.

GEORGE H. HULETT AND FRANK E. HULETT, OF CLEVELAND, OHIO.

SYSTEM AND APPARATUS FOR LOADING VESSELS.

1,327,327.

Specification of Letters Patent.

Patented Jan. 6, 1920.

Application filed October 29, 1918. Serial No. 260,107.

To all whom it may concern:

Be it known that we, GEORGE H. HULETT and FRANK E. HULETT, citizens of the United States, and residents of Cleveland, 5 in the county of Cuyahoga and State of Ohio, have invented certain new and useful Improvements in Systems and Apparatus for Loading Vessels; and we do hereby declare the following to be a full, clear, and 10 exact description of the invention, such as will enable others skilled in the art to which it appertains to make and use the same.

Our invention relates to an improvement in a system and apparatus for loading vessels with coal, ore and like material.

With the apparatus and systems now in use for handling coal and ore on piers, it is necessary in order to load and trim at all hatches of one or more vessels being loaded, 20 to equip the pier with a large number of fixed storage and loading bins so as to have one bin opposite or within loading distance of each hatch of the vessel or vessels being loaded, all the intermediate or end bins 25 being in the meanwhile idle.

The most modern piers in use at the present time have the fixed bins or pockets about twenty-four feet apart with mechanism at each for depositing the coal in the hatch. 30 Such a system with the necessary chute and conveyer mechanism for each bin, makes the construction, maintenance and operation very expensive, and the object of our invention is to greatly reduce the cost and expense by providing a series of traveling bins adapted to be moved to positions opposite the hatches and receive the coal from pier cars and discharge it into the vessel, and our invention consists in the arrangement 35 of the tracks and in the parts and combinations of parts as will be more fully explained and pointed out in the claims.

In the accompanying drawing, Figure 1 is a diagrammatic view in side elevation of 40 the railroad track system on the pier and at the shore end of the latter; Fig. 2 is a similar view in plan of the same; Fig. 3 is a diagrammatic view in vertical section through the pier and trestle at two points 45 showing the up track for loaded cars at two elevations within the trestle structure and Fig. 4 is a view in side elevation.

In the operation of our system the coal or ore cars which convey the coal from the 55 mines to the pier, are carried on tracks 5 to the dumper 6 and the coal dumped into

conveyer cars 7 which will be hereinafter referred to as pier cars. These pier cars are located on tracks 8, in a position to receive the coal from the dumpers and after 60 having been filled, are self propelled, pushed or pulled from tracks 8 onto and up track 9 which we prefer to be about 1½ or 2 per cent. grade. This up track 9 is located centrally with relation to the trestle 16 built up 65 on the pier, and passes upwardly through the trestle 16 as shown in Fig. 3 and emerges at the top near the outer end of the trestle and pier, room however being provided at the outer end of the trestle for switching 70 the pier cars from track 9 onto either of the tracks 10.

By locating the up track 9 within the trestle and discharging the contents of the pier cars after they have been switched onto 75 the return tracks 10, it is possible to provide an easy up grade for the loaded cars, as shown in Fig. 1, while the empty pier cars return to the dumper down the steeper grade 17.

After the pier cars have been pushed or pulled up the tracks 9 and switched over onto the side tracks 10, which are preferably level throughout that part of the pier over which the bins 11 are movable, the loads are 80 dumped onto the bins and the cars then returned to the dumps for refilling.

The cars on tracks 5 after having their contents dumped into the pier cars are switched at 13 onto tracks 14, and are then 85 free to be returned to the mines for reloading.

With this system the contents of the coal cars are emptied into the pier cars which latter are specially constructed for use on 90 the pier. All have dump bottoms, and some are arranged to dump into a bin at one side of the trestle and others into bins at the opposite side as shown in Fig. 3.

The piers 15 which are from twelve hundred 100 to fourteen hundred feet long, are of a width to accommodate the trestle having three parallel tracks 9 and 10 and tracks 17 which are located on the pier at the opposite sides of the trestle as shown in Fig. 3.

The movable bins 11 may be of any approved construction and the frames carrying the bins are mounted on wheels which traverse the tracks 17 on the pier 15. These bins are approximately the height of the 110 space between the piers and top of the cantilever trestle and are overhung by the latter

so as to bring the tracks 10 well over the open top of the bins so that the coal discharged through the bottom of the pier cars 7 will fall directly into the bins 11. The 5 top of the bins may (not absolutely necessary) carry means for engaging the underside of the top of the trestle, as shown at 18 for preventing the possibility of the bins tipping outwardly when the chutes are projected. The pier cars 7, are adapted to dump at the side or bottom and by the cantaliver construction of trestle shown, we are enabled to carry the pier cars over the bins so that all of the coal discharged from the 15 cars falls into the bins. Each bin frame carries endless conveyer frame or chute 18, the belt 19 of which is actuated by a motor 20 and suitable gearing. The conveyer frame is preferably made in sections hinged together as shown, and is supported by cables 21 and 22 the free ends of which are secured to the drums 23, which are actuated by the motor 20 and suitable gearing, or by an independent motor as may be preferred. The 20 rear end of the conveyer frame rests under the lower end of the bin, which open end is closed and the flow of coal therefrom controlled by a gate, and the coal which falls on the conveyer belt is carried out and deposited in the hatch, suitable guards 24 and 25 being provided for guiding and directing the coal into the hatch. With this construction, the conveyer frame can be raised and lowered as shown in full and dotted lines in 30 Fig. 3 and can be turned upwardly out of the way of the vessel so as not to interfere with its movement in approaching or leaving the pier.

The pier cars after discharging their contents into the bin continue their travel inwardly toward the shore end of the trestle, and pass down the steeper inclined trackway 17 to the trackway 8 where the cars are re-loaded at the dumpers and are again moved 40 upwardly onto the pier and trestle and their contents discharged into the bins. The movements of these cars on the pier are always a progressive one, that is to say they ascend the trestle on one track and return 45 on another so that there is no interference between the loaded and empty cars while 50 on the pier.

It is evident that many slight changes might be resorted to in the relative arrangement of parts shown and described without departing from the spirit and scope of our invention. Hence we would have it understood that we do not wish to confine ourselves to the exact construction and arrangement 55 of parts shown and described, but

Having fully described our invention what we claim as new and desire to secure by Letters-Patent, is:

1. In a system of loading vessels, a pier or 60 dock having an elevated trestle thereon, an

inclined up track leading from the shore end of the pier through the trestle to the top thereof, a track located at a side of the trestle, switch connection between the up track and side track, an inclined down track 70 leading from the shore end of the side track down to the starting point of the up track and cars adapted to travel on said tracks and dump their contents into the bins located on the pier and convenient to a vessel 75 moored to the pier.

2. In a system of loading vessels, a pier or dock having an elevated trestle thereon, a car dumper, tracks leading to and from the car dumper, an inclined up track for pier 80 cars leading from the car dumper through the trestle to the top thereof, a track located on the trestle adjacent the side thereof, a switch connection between the up track and the side track, an inclined down track 85 leading from the shore end of the side track on the trestle to the lower end of the up track and pier cars adapted to travel on said tracks and dump their contents into bins located on the pier and in a plane below the top of the trestle.

3. In a system of loading vessels, a pier having a trestle thereon, an inclined up track passing upwardly and outwardly through the trestle to the top thereof, a track 90 on top and near one side of the trestle, a switch connection between said tracks at the outer end of the trestle and an inclined track leading from the shore end of the side track on the trestle to the lower end of the upwardly inclined track, whereby a car first passes up the inclined track to the top of the trestle, thence back on the top of the trestle toward the shore end of the latter, and thence down an inclined track back to 100 the starting point.

4. The combination of a pier having a trestle thereon, an up track leading from the shore end of the pier to the top of the trestle, a track on the trestle adjacent one side, and 110 a bin movably mounted on the pier in a plane below said side track, the said bin having means for discharging coal therein into the hold of a vessel, and a down track leading from the shore end of the side track 115 to the starting point of the up track.

5. The combination of a pier having a trestle thereon, an up track leading from the shore end of the pier to the top of the trestle, a track on the trestle adjacent one 120 side of the latter, a traveling bin on the pier below the side track and overhung by the latter, means for discharging the contents of the bin into the hold of a vessel and a track leading from the shore end of the side track on the trestle down to the starting point of the up track.

6. The combination of a pier, a cantaliver trestle thereon, a series of traveling bins mounted on the pier with their tops below 125

the top of the trestle and overhung by the latter, means for discharging the contents of the bins into a vessel moored at the side of the pier, a track leading to the top of the trestle, a track on the trestle at the side adjacent the bins, a switch connection between the tracks on the pier, a track leading from the side track at the shore end to the starting point of the up track and dump 10 cars for carrying coal to the top of the

trestle and depositing it into the traveling bins.

In testimony whereof, we have signed this specification in the presence of two subscribing witnesses.

GEORGE H. HULETT.
